UNITED STATES PATENT OFFICE.

CHARLEY H. STEES, OF PHILADELPHIA, PENNSYLVANIA.

DESIGN FOR A BADGE.

40,573.

Specification for Design. Patented Mar. 15, 1910.

Application filed December 16, 1909. Serial No. 533,494. Term of patent 14 years.

To all whom it may concern:

Be it known that I, CHARLEY H. STEES, a citizen of the United States, residing at Philadelphia, in the county of Philadelphia and State of Pennsylvania, have invented a new, original, and ornamental Design for Badges, of which the following is a specification, reference being had to the drawing forming part thereof.

The figure is an elevation of a badge, showing my new design.

I claim:

The ornamental design for a badge as shown.

CHAS. H. STEES.
